[57] **CLAIM**

A ornamental design for a picture frame, substantially as shown and described.

DESCRIPTION

FIG. 1 is a top front and right side perspective view of a picture frame showing my new design;

FIG. 2 is a front elevational view thereof, the rear not shown being devoid of ornamentation;

FIG. 3 is a left side elevational view thereof;

FIG. 4 is a right side elevational view thereof;

FIG. 5 is a top plan view thereof, the bottom not shown being devoid of ornamentation;

FIG. 6 is a top, front, right side perspective view of a second embodiment of that shown in FIG. 1;

FIG. 7 is a front elevational view thereof, the rear not shown being devoid of ornamentation;

FIG. 8 is a left side elevational view thereof;

FIG. 9 is a right side elevational view thereof;

FIG. 10 is a top plan view thereof, the bottom not shown being devoid of ornamentation;

FIG. 11 is a top, front, right side perspective view of a third embodiment of that shown in FIG. 1;

FIG. 12 is a front elevational view thereof, the rear not shown being devoid of ornamentation;

FIG. 13 is a left side elevational view thereof;

FIG. 14 is a right side elevational view thereof;

FIG. 15 is a top plan view thereof, the bottom not shown being devoid of ornamentation.
